UNITED STATES PATENT OFFICE.

HARRY W. HILL, OF SOUTHERIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

LENS-GRINDING MACHINERY.

Application filed July 26, 1920. Serial No. 399,049.

To all whom it may concern:

Be it known that I, HARRY W. HILL, a citizen of the United States, residing at Southbridge, in the county of Worcester and State of Massachusetts, have invented certain new and useful Improvements in Lens-Grinding Machinery, of which the following is a specification.

This invention relates to improvements in lens grinding machinery and has particular reference to a novel and improved construction of machine for use in the grinding or polishing of spherical surfaces, and particularly adaptable for use in connection with the formation of bifocal lenses from a single piece of glass.

The principal object of the present invention is the provision of a novel and improved construction of machine in which the several parts shall be rigidly connected or associated to maintain a predetermined fixed relationship one to the other to avoid any aberrative effect at the line of joinder of the two surfaces being operated upon.

A further object of the invention is the provision of a simple and readily adjustable mechanism particularly designed for the polishing of the central or reading portion of a one piece bifocal lens, which may be readily accurately positioned to operate exactly to but not extend at all over the dividing line between the reading and distance portions.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a side elevation with parts in section of a machine embodying my improvements.

Figure II represents a side elevation with one of the tool holding arms in raised position.

Figure III represents a plan view of the structure as shown in Figure I.

Figure IV represents a detail view of the adjustable tool engaging arm.

In the drawings the numeral 1 designates

the main bed or frame having journaled therein the lower spindle 2 driven as through the pulley 3 and bearing at its upper end the lens holder 4 for the lens or glass disc 5 to be operated upon. Said lens as illustrated is intended to be of bifocal form, that is, having an outer or major portion and a central or reading portion 6 which may either join each other in a merged line of joinder, or in a cliff with the parts of unequal height, as may be preferred, my machine being equally adaptable for the construction of either of these difficult to manufacture types of lenses, as well as being entirely practicable for use in connection with the formation of plain spherical surfaces.

Rising from the bed 1 is the supplemental frame member 7 having pivoted at the top thereof the link 8 which in turn has pivoted to it the tool arm 9 provided with the angularly adjustable head 10 having bearings on the spindle 11 of the tool 12 shown as positioned to grind the outer or distance portion of the lens. The in and out position of the tool may be suitably adjusted as through rotation of the adjusting screw 13 which intermediately engages the link 8.

Supplementing the action of the arm 9 and tool carried thereby are a pair of arms 14 pivoted to the frame 7 preferably slightly in advance of the point of pivotance of the link 8, said arms extending forward but spanning the arm 9 and terminating at their forward ends in the rearwardly curving cross piece member 15 provided at one end with the pivot receiving aperture 16 and at the opposite end with the slot 17.

A tool engaging arm 18 is pivoted at one end as at 16 and is intermediately provided with a depending pin 19 adapted to engage the tool 20, while at its opposite end it is provided with the boss 21 through which passes the adjusting screw 22. This screw screws into the boss or lug 23 on the arm 14 and has a head portion 24 bearing against the front of the arm 18, while mounted rearwardly thereon between the boss and arm is a spring 25 normally pressing the arm forward against the tightening action of the screw. By rotation of the screw the arm will be swung inward about the pivot 16 as a center to exactly correctly position the tool 20 with its edge coming just to the line of joinder between the reading and distance portions of

the lens. When the arm has been exactly adjusted it may then be locked in adjusted position as by the clamp screw 26 which extends downwardly through the slot 17 and is screwed into the arm 18, tightening of this screw securely clamping the parts 15 and 18 together against any relative pivotal or sliding movement.

I would call particular attention to the inwardly arcing form of the members 15 and 18, in that they on account of this shape afford a better view of the work and facilitate more satisfactory adjustment of the tools 12 and 20 than would be the case were the cross bar straight across, tending to interfere with the view either around or thereover of the tool 12.

I also would call attention to the fact that the space between the arms 14 is such that the arms may be swung upward as desired to disengage the pin 19 from the tool 20 when desired and may be locked in raised position as by the latch member 27, as is illustrated in Figure II, or the arm 9 may be raised without reference to the arms 14, when desired suitable weights 28 acting through flexible connections 29 serving to hold each of the arms separately and independently down toward the work during the grinding or polishing operation. It will be seen that either the reading or distance portion, or both, may be ground by my improved machine and either surface independently inspected and the operation stopped at any desired point without interfering with the use of the other tool, and in this way I can quite satisfactorily produce a two part merged surface bifocal lens with my machine without the necessity of separately performing the several operations and changing the lens from one machine to the other, as has hitherto been necessary in the production of lenses of this type.

It will also be understood that by properly relating the weights 28 on the two arms they may be caused to work down into the glass at substantially even rate of speed so as not to disturb the relationship of the two surfaces one to the other.

I claim:

1. A machine of the character described including a frame, a spindle journaled in the frame and adapted to receive a lens holder, an adjustable spindle bearing arm carried by the frame and movable in a direction toward and away from the lens holder spindle, a spindle carried by the bearing

arm and a second arm in the form of a yoke carried by the frame and spanning the last mentioned spindle, said second arm being held against movement relative to the frame, a second lap engaging spindle carried by said arm and adjustable connections between the arm and spindle to vary the in and out position of the spindle with respect to its arm.

2. In a machine for grinding bifocal lenses, the combination with a frame, of a lens bearing spindle rotatably mounted in the frame, an arm pivotally connected to the frame and bearing a lap engaging spindle, and a second arm pivotally connected to the frame adjacent the point of attachment of the first and spanning said first arm, said second arm also bearing a lap engaging spindle whereby either of said arms may be swung out of engagement with the lens without disturbing the other.

3. In a machine for grinding bifocal lenses, the combination with a frame, of a lens bearing spindle rotatably mounted in the frame, an arm carried by the frame and bearing a lap engaging spindle, and a second arm carried by the frame adjacent the point of attachment of the first and spanning said first arm, said second arm also bearing a lap engaging spindle, means for bodily moving one of the arms to vary the position of the spindle carried thereby, and means for shifting the other lap engaging spindle with respect to its arm.

4. A machine of the character described, the combination with a lens bearing spindle, of a pair of lap engaging spindles for cooperation with the lens engaging spindle to respectively engage the reading and distance portions of a lens, and means for properly supporting said latter spindles in operative position, said means including a transversely adjustable arm carried by the frame and having an angularly adjustable connection with one of the spindles, a second non-adjustable arm also carried by the frame, an oscillatable plate carried by said arm and rigidly engaging the other of said spindles, and means for securing the plate and its spindle in desired adjusted position.

In testimony whereof I have affixed my signature, in presence of two witnesses.

HARRY W. HILL.
